UNITED STATES PATENT OFFICE.

MILLS S. PHILLIPS, OF TACOMA, WASHINGTON.

CAR-ENUMERATING DEVICE.

1,421,023.

Specification of Letters Patent. Patented June 27, 1922.

Application filed August 15, 1919. Serial No. 317,765.

To all whom it may concern:

Be it known that I, MILLS S. PHILLIPS, a citizen of the United States, residing at Tacoma, in the county of Pierce and State of Washington, have invented certain new and useful Improvements in Car-Enumerating Devices; and I do hereby declare the following to be a full, clear, and exact description of the invention, such as will enable others skilled in the art to which it appertains to make and use the same.

This invention relates to registering devices and while particularly applicable to car enumerating devices is not limited thereto.

An object of this invention is to provide a means for counting cars as they go in at one end of a siding.

A further object of this invention is to provide a means so that an engineer in entering a siding will immediately know the number of cars already in said siding and an engineer, conductor or switchman on leaving the siding can instantly ascertain from the other end the number of cars in said siding and by looking at the dial can also instantly see whether another crew is working upon the same siding from the other end.

A further object of this invention is to provide a means for counting the cars both going in and coming out and subtracting those going in one way in order to keep a positive record.

A further object of this invention is to be able to enumerate the cars left standing on a side track without the delay of the switching crew.

A further object of this invention is to enable the brakeman on a dark and cloudy day or in the night time to see how much room there is to store cars on each siding.

A further object of the invention is to provide a danger signal showing when cars on a siding are not left in the clear.

A further object of this invention is to register cars in going into the car barns while passing over certain tracks and to provide means for recording and noting the number of cars at an extreme distance from the station.

With these and other objects in view the present invention comprises certain novel construction, combination and arrangement

of parts such as will be hereinafter more fully described and claimed.

In the drawing,

Figure 1 is a view of the apparatus looking on the dial face and also showing its remote connection to a car rail.

Figure 2 is a side view of an ordinary car rail showing the means of attachment of this apparatus thereto.

Figure 3 is a longitudinal cross section of the registering portion taken diametrically through the dial.

Figure 4 is a rear elevation of the registering portion.

Figure 5 is a diagrammatic view of the indicators in a series.

Like characters of reference indicate corresponding parts throughout the several views.

The present invention is disclosed in the drawing as comprising a dial 1 rotatable and carrying at the other end of a shaft 2 a gear 7 co-meshing with a corresponding gear 6, the said gear 6 on a shaft 6' actuated by ratchets 3 and 4, fixed thereon, the said ratchets being set in reversed relation, one of said ratchets rotating the shaft 6' in one direction and the other of said ratchets rotating the shaft in the other direction. A retention wheel 23 is fixedly mounted on shaft 6' and engaged by a spring contact 24 to prevent free rotation of the shaft. Angular pawls 10 and 10' are pivoted one on each side of the dial to arms 10^a and 10^b, which are in turn pivoted on shaft 6' so that pawls 10 and 10' can engage the ratchets 4 and 3, respectively, on opposite sides. These pawls

are normally out of engagement with the ratchets, but are thrown into engagement by means of rods 11 connecting them to slidable cores in the electromagnets 8 and 8'. The dial has upon its face an index finger 19. It is obvious that this arrangement may be reversed and the index finger may be rotated and the dial kept in fixed relation. Coils 8 and 8' are connected by separate current wires 12 and 12' to springs 13 and 13' and 100 also by a common wire 12" to a common conductor 15 closing a circuit when contact is made with contact member 14.

Roller 17 is loosely mounted on an oscillatory arm 17' and member 17' is fixedly mounted on shaft 17". Shaft 17" is suit-

ably mounted in bearings. 14' is another oscillatory arm fixed to shaft 17" and carries loosely mounted a roller 14. The shaft mount on arm 14' for roller 14 is extended 5 into an eye 20. Eye 20 engages a spring 21. Spring 21 is mounted to standard 22. Spring 21 normally holds arm 14' and therefore arm 17' in an upright position. Springs 13 and 13' and also common conductor 15 are in the 10 path of roller 14. Roller 14 is an electrical conductor.

Coil 8 is connected by wire 12 with contact member 13. Coil 8' is connected by wire 12' with contact member 13'. Coils 8 and 8' 15 have a common complementary circuit wire 12" leading to common conductor 15. When roller 14 is swung over against spring 13 until roller 14 touches also common conductor 15 it closes a circuit through roller 14 20 from members 13 and 15 and from wires 12 and 12" leading respectively to members 13 and 15. When roller 14 is swung over in the reverse direction against spring 13' until roller 14 touches common conductor 15 it 25 closes a circuit through roller 14 from members 13' and 15 and from wires 12' and 12" leading respectively to members 13' and 15. When the circuit is closed through wire 12 and wire 12" it energizes coil 8 to operate 30 pawl 10 and turns the dial 1 counterclockwise. When the circuit is closed through wire 12' and wire 12" it energizes coil 8' to operate pawl 10' and turns dial 1 clockwise.

As for instance when the roller 14 is 35 swung against spring 13' to contact with conductor 15 it makes the dial register in one direction; when it is thrown against 13 and conductor 15, it makes the dial rotate and register in the other direction. This 40 enables the adding and subtracting of cars. As for instance when a car passes over rail 18 contact of the car wheels upon the rotor 17 causes the contact point 14 to swing over in the direction in which the car is going and 45 come in contact with spring 13' and conductor 15. This will cause the dial to indicate the number of wheels which have gone over in that direction. If, on the other hand, the cars go back in the reverse direction, the 50 rotor 14 is swung over to contact with spring 13 and conductor 15 and the dial rotated in the reverse manner thereby subtracting the numbers of cars going in the reverse direction. This gives a positive record of all cars 55 left upon the siding or other place where the record is desired to be kept.

When used in a series I use a slightly different mechanism as shown in Figure 5. Instead of common conductor 15, I use a pair 60 of springs 15^b and 15^c or 15^d 15^e similar to springs 13 and 13'. These may be superposed of springs 13 and 13' or set in the same relation as common conductor 15 is shown in Figures 1 and 2. If superposed 65 then the relation is such that roller 14 when

swung to the left will bring spring 13 into contact with spring 15^b, and if swung to the right roller 14 will bring spring 13' into contact with spring 15^c.

If springs 15^b and 15^c are set in the same 70 relation as the common conductor 15 as shown in Figs. 1 and 2 then roller 14 will function as a conductor as in the arrangement shown in Figures 1 and 2. When one register is used at each end of a siding and 75 it is desired to record the ingoing cars from either or both ends as positive and the outgoing as negative, similar coils for respective registers are connected to similar poles illustrated by current wire 12^a connecting 80 coil 8 of the register at the left with coil 8 of the register at the right and current wire 12^b connecting coil 8' with coil 8' of the respective registers. The other poles of these coils are similarly connected by current wires 85 12^a and 12^c. Wire 12^a also connects with and joins springs 15^b and 15^c. Wire 12^a also extends to a pole of a battery 12^e. From the other pole of battery 12^e extends a wire 12^d which connects with spring 13 of the mechanism shown at the left and spring 13' of the mechanism shown at the right. Current 90 wire 12^a similarly extends to a pole of a battery 12^f from the other pole of which battery extends a current wire 12^b. Current 95 wire 12^b connects with and joins springs 13' of the mechanism shown at the left with spring 13 of that shown at the right. Wire 12^a also connects with and joins springs 15^c and 15^d. Thus when a car enters a siding 100 from the side at the right of Figure 5 it causes roller 14 to swing to the left and close a circuit through springs 15^d and the spring 13 at the right. This closes a circuit through battery 12^f and energizes coils 8 to rotate 105 dial 1 clockwise. The same effect would be had by a car entering from the side shown at the left of the drawing by closing a circuit through springs 13' and 15^c. A negative effect would be had by a car passing from 110 the middle outward in either direction as such car if passing to the left would close a circuit through springs 13 and 15^b or if passing to the right from the middle would close a circuit through springs 13' and 15^d. Closing either of these last named circuits 115 would cause battery ^c to energize coils 8' to rotate dial 1 counterclockwise. Not only is this dual arrangement valuable in recording the actual number of cars on a siding 120 whether taken in from one end or the other but also it enables a crew entering at or working at one end of a siding to determine just what is going on at the other end. By varying the wiring connections I can further 125 use this device in a series as an efficient block signal system.

What I claim is:

An electrical contact maker comprising in combination with a car rail, of a shaft ex- 130

tending transversely thereof and having a lever arm on one end carrying a rocking roller adapted to be engaged by the flange of a car wheel to rock said shaft in the direction of movement of said car wheel, a contact roller carried by said shaft pivoted eccentric thereto, contact members arranged on each side of said contact roller and spring

means secured to the contact roller eccentric and pivoted above and in a vertical plane 10 passing through the shaft controlling said shaft to maintain said rocking roller in a normally elevated position.

In testimony whereof I affix my signature.

MILLS S. PHILLIPS.
